CLAIM

The ornamental design for a wireless speaker, as shown and described.

DESCRIPTION

FIG. 1 is a perspective view of a wireless speaker in accordance with the present invention;

FIG. 2 is a front view of the wireless speaker of FIG. 1;

FIG. 3 is a back view of the wireless speaker of FIG. 1;

FIG. 4 is a left side view of the wireless speaker of FIG. 1;

FIG. 5 is a right side view of the wireless speaker of FIG. 1;

FIG. 6 is a top view of the wireless speaker of FIG. 1; and, FIG. 7 is a bottom view of the wireless speaker of FIG. 1. The broken lines in FIG. 3 are for the purpose of illustrating environmental features and form no part of the claimed design.
